UNITED STATES PATENT OFFICE.

MARTIN B. MC LAUGHLIN, OF MALDEN, MASSACHUSETTS.

ELEVATOR-SHAFT DOORLOCK.

Application filed February 5, 1923. Serial No. 616,908.

This invention relates to door locks more particularly designed for uses on doors leading to the interiors of dumb waiter shafts and the like, and has for its chief object the provision of a lock which permits the door to be opened readily when the elevator car is stationary opposite it so that it may be loaded or unloaded through the door opening, but which prevents opening 10 of the door at other times without the use of a key. By this means the normal operation of the elevator is rendered safe for the user, while access to the shaft may be had for inspection and repair by those specially 15 trained for this purpose who may be provided with keys.

For a more complete understanding of this invention, together with further objects and advantageous details and combinations 20 of parts, reference may be had to the accompanying drawings in which

Figure 1 is a fragmentary elevation of an elevator shaft showing the device of the invention applied to a swinging door.

Figure 2 is a fragmentary horizontal section on line 2--2 of Figure 1.

Figure 3 is a side elevation of the lock showing its manner of mounting on the door.

Figure 4 is a section on line 4--4 of Figure 3.

Figures 5, 6, 7, and 8 are views similar to Figures 1, 2, 3, and 4, respectively, but showing the device as applied to a sliding door.

Figure 9 is a section of a modified form of lock taken along the lines 9--9 of Figures 10 and 11.

Figures 10 and 11 are sections on lines 40 10--10 and 11--11, respectively, of Figure 9.

Referring first to the construction illustrated in Figures 1 to 4, 1 indicates a portion of an elevator casing having a doorway 2 in one wall thereof which may be closed by a door 3 hinged thereto at 4. A portion of the elevator car is shown at 5 which is slidable within the shaft or casing 1. The lock for the door is shown at A and has projecting therefrom a rock shaft 6 accessible from the forward face of the door as by means of a knob 7. The rock shaft 6 is journaled in opposite walls of a casing

8 within which the operative mechanism of the lock is mounted and has fixed thereon 55 within the casing a cam 9. This cam is adapted to bear against the intermediate portion 10 of a bar or lever 11. This bar or lever 11 is loosely slidable on a pin 12 projecting inwardly from a side wall of the 60 casing 8 and is normally held against a head 13 on the pin by means of a spring 14 which, as shown, surrounds the pin 12 and reacts between a portion of the side wall of the casing and the member 11. The 65 bar 11 has also fixed thereto at its opposite end a spring 15 which, as shown, is attached at one end to the bar 11 and at its other end to a lug 16 projecting from one wall of the casing. Both springs 14 and 70 15 act in the same direction to urge the bar or lever 11 against the cam 9. The spring 14, however, is of relatively greater strength than the spring 15 so that if the bar is otherwise unrestrained, rocking motion imparted to the shaft 6 to bring the high point of the cam against the bar 11, causes the spring 15 to yield, while the spring 14 remains substantially unaffected, by which 75 action the bar 11 is caused to turn about a 80 fulcrum adjacent its lower end. If, however, the upper end of the bar 11 adjacent the spring 15 is held against motion pressure of the cam 9 on the intermediate portion of the bar effects a compression of the spring 85 14 and causes a bodily motion of the lower end of the bar 11. It will thus be seen that 90 this bar acts as a lever which may be moved about one or the other of a pair of fulcrum, one of these fulcrum being its center of 95 oscillation under normally unrestrained conditions and the other becoming active when the first is held inactive. The cam 9 is normally held with its high point out of contact with the bar by means of a spring 100 17 fixed to a lug 18 extending from the cam at one end, and at its other end attached to a portion of the casing. For the purpose of preventing movement of the upper end of the bar 11, an arm or member 20 is shown 105 pivoted at one end in a slot 19 therein, its opposite end extending out through a slot 21 in the casing. This arm 20 is normally held to extend substantially perpendicularly to the member 11 by means of a 110 spring 22 reacting between a lug 23 on the

arm 20 and a lug 24 projecting from the bar 11. For cooperating with this arm 20 the elevator car 5 has a cam bar 25 fixed thereto, which when the elevator car is in position opposite the doorway extends, as shown in dotted lines in Figure 1, adjacent the end wall of the casing 8 in position to be contacted by the end of the arm 20 on a slight outward movement thereof. The ends 10 of this bar 25 are preferably curved away from the casing 8 as shown at 26 and the arm 20 is mounted yieldably as above described in order that should the car be in motion when the cam 9 is actuated, the end of 15 the arm will be engaged thereby and the arm turned from its normal position so as to permit the upper end of the bar 11 to move instead of compelling movement of the lower end. The lower end of the bar 11 20 extends through a slot 30 in the bottom wall of the casing 8 and carries a latch element 31 adapted to cooperate with a stationary latch element 32 fixed to the inner wall of the elevator shaft. If now the elevator 25 is in stationary position opposite the doorway and the knob 7 be turned, the cam 9 acts against the central portion of the bar 11, forcing the central portion of this bar away from the shaft 6, the spring 15 yielding, due to its comparative weakness with 30 relation to the spring 14 until the arm 20 contacts the member 25 on the elevator car, while the engagement of the latch 31 with the latch 32 is substantially unaffected. As 35 soon as the arm 20 is stopped by the member 25 further motion of the cam acts to move the lower end of the bar 11 against the tension of the spring 14 causing the latch 31 to move out of engagement with its co- 40 operating member 32. When this has been effected the door may be opened by pulling outwardly on the knob 7. In case the elevator car is not in position opposite the opening, or is in motion when the arm 20 45 strikes the member 25, the entire movement of the cam 9 is expended in moving the upper end of the bar 11 against the action of the spring 15 so that the latch member 31 fails to become disengaged from the 50 member 32, even at the extreme limit of action of the cam 9. Hence when the car is not in position or is not stationary the door is normally not unlocked by turning the knob 7 but is retained in fully closed 55 position.

It is sometimes desirable, however, to inspect the interior of the elevator shaft and for this purpose the door should be capable of being opened when the elevator car is not opposite thereto. This, however, should only be done by one authorized to make such inspection and normally not by the operator of the elevator. For this purpose a key may be employed to be in the possession of the 60 person authorized to inspect the interior of

the shaft, this key being so related to the locking mechanism that when inserted therein, turning of the knob 7 acts to unlock the door even though the elevator car is not in stationary position opposite the door opening. This may be done in the present mechanism by forming an opening for the key through the door and through one or both walls of the casing 8 in position so that when the key is inserted, it prevents 75 movement of the upper end of the bar 11. For this purpose the key shown in section at 35 may be inserted adjacent the upper end 36 of the bar 11 on the same side thereof when it is in normally locked position as 80 the arm 20. This key acts then as a stop to prevent bodily movement of the upper end of the bar so that turning of the cam 9 acts to move the latch member 31 out of cooperative relation to its mating member 32 so 85 that the door may be opened irrespective of the position of the elevator car.

Referring now to Figures 5 to 8 inclusive, the lock is shown as lightly modified for application to a sliding door. Referring to 90 these figures the bar 11' is mounted in the same manner as the bar 11 of the first form described within the casing 8 and carries at its upper end a yieldable pivoted arm 20 normally held projected through a slot 21 95 of the casing by means of a spring 22, the arm 11' being held against the cam 9 by means of a relatively weak spring 15 and a relatively strong spring 14, the bar sliding loosely along the pin 12. The movable latch 100 member carried by the bar 11' is shown at 31' and cooperates with a fixed latch member 32'. In place of the knob 7 and the rock shaft 6 a lever 7' may be employed which, if desired, may rest in a depressed portion 105 7'a in the outer face of the door, this portion serving as a hand grip in order that the door may be slid upwardly along suitable ways in the elevator shaft casing. A key slot for a key 35 which may prevent bodily 110 movement of the upper end of the arm 11' may be employed positioned in the same manner as indicated in Figures 1 and 4. With this form of mechanism the latch member 31 is provided with a hook engaging under the latch member 32 so that in 115 normal locking position the door 3' may not be raised. When the elevator car is in stationary position, however, by raising the lever 7', the cam 9 is rocked to move the bar 11' and as its upper end is prevented from free movement by the arm 20 engaging the member 25 on the elevator car, the latch 31' is moved out from beneath the fixed latch member 32', whereupon continued upward pull on the lever 7' acts to raise the door 3'. Insertion of the key 35 acts in the manner before described to prevent 120 bodily movement of the upper end of the arm 11' so that by raising the lever 7' the 125 130

unlatching of the door is effected even though the elevator car is not stationary opposite the door opening.

In place of the latch members 31, 32, 31', 5 32', a latch bolt carried by the lock may be employed to engage in a suitable socket in the elevator shaft casing. Such a construction is shown in Figures 9 to 11. Referring to these figures, the lock casing 10 is indicated at 50 and projectable therefrom to engage a suitable socket in the casing 51. As shown this latch bolt slides between upper and lower guides 52 and 53 carried by the casing 50 and its 15 lower inner end is provided with a recess 54 in which extends the upper end of a lever 55. This lever is pivoted on a pin 56 projecting inwardly from one side wall of the casing 50 and its lower end is forked as at 20 57 to engage over a pin 58 projecting from the lower end of a floating bar 59. This bar 59 corresponds in function to the bars 11 and 11' of the forms before described, riding loosely at its lower end on a pin 60 25 and having its central portion 61 pressed against the face of a cam 62 carried by a rock shaft 63 by means of an upper comparatively weak spring 64 and a lower comparatively strong spring 65. The cam 62 is 30 normally held rocked to a position permitting the bar 59 to be moved to its inner limit of motion by the springs 64 and 65, as by means of a spring 66. Pivoted adjacent the upper end of the bar 59 in a slot 35 69 therein is an arm 70 projecting through a slot 71 in the casing and normally held in substantially perpendicular position relative to the bar 59 by the spring 72. The casing also is provided with keyhole slots, 40 preferably in opposite faces, for the reception of a key, shown in section at 75 in Figure 11, so positioned as to prevent bodily movement of the upper end of the bar 59 by the action of the cam 62. With 45 this construction when the upper end of the bar 59 is held from movement, either by the stationary presence of the member 25 of the elevator car, as above described in connection with other forms of the invention, or by means of the presence of the key 75, rocking of the shaft 63 to cause the cam 62 to move the bar 59 effects bodily motion of the lower end thereof by which the lever 55 is rocked to retract the latch bolt 55. 51. If the upper end of the bar 59 is free 55 to move, however, as when no key is in position and the elevator car is out of cooperative relation to the door opening or is moving, rocking of the shaft 63 merely effects 60 a bodily movement of the bar 59 without in any way effecting the lever 55 and hence without retracting the latch bolt.

Having thus described certain embodiments of this invention, it will be evident to those skilled in the art that many changes

and modifications might be made therein without departing from its spirit or scope as defined by the appended claims.

I claim:

1. The combination with a shaft, a car 70 therein, a doorway for said shaft through which access may be had to said car, and a door for closing said doorway, of a latch for holding said door closed, said latch including a member movable toward the interior 75 of said shaft to contact with the car therein only when said car is opposite to said doorway, and means actuatable to release said latch only when said member is in such contacted position, said member being movable by 80 movement of said car after such contact in a manner to render inoperative said releasing means.

2. In combination with a shaft, a car 85 therein, and a doorway for said shaft through which access may be had to said car, of a door for closing said doorway, a latch for holding said door closed, means normally actuatable to release said latch to permit the door to be opened only when said car is in 90 cooperative relation to said doorway, and means operatively associable with said latch acting to permit said latch to be released when said car is out of cooperative relation to said doorway.

3. A device of the class described, comprising cooperating latch members, means actuatable under certain conditions only to release said latch members, and means associable with said members permitting said 100 means to be actuated to release said members under other conditions.

4. In combination with a shaft, a car in said shaft, and a door for closing a doorway in said shaft through which access may 105 be had to said car when it is positioned opposite to said doorway, of cooperating latch members on said door and car, a rockable member associated with said latch members and projectable into said shaft to contact 110 with said car only when said car is opposite to said doorway, means actuatable to so project said rockable member and actuatable only when the extent of such projection is limited by its contact with said car to release said 115 latch member, said rockable member being rocked by movement of said car after such contact to render said actuatable means inoperative to release said latch members.

5. In combination with a shaft, a car 120 therein, and a door for closing a doorway in said shaft through which access may be had to said car when opposite said doorway, of a lock for said door comprising cooperative latch members on said door and shaft, one of said members being movable toward and from the other of said members, a movable element operatively associated with said movable latch member, means for moving said element, and means for so sup- 125

porting said element that it is moved by said moving means in a manner inoperative to move said movable latch member when the car is out of cooperative relation to said doorway and in a manner to release said latch members when said car is in cooperative relation to said doorway.

6. In combination with a shaft, a car therein, and a door for closing a doorway in said shaft through which access may be had to said car when opposite said doorway, of a lock for said door comprising cooperative latch members on said door and shaft, one of said members being movable toward and from the other of said members, a movable element operatively associated with said movable latch member, means for moving said element, means for so supporting said element that it is moved by said moving means in a manner inoperative to move said movable latch member when the car is out of cooperative relation to said doorway and in a manner to release said latch members when said car is in cooperative relation to said doorway, and means associable with said element causing it to be moved by said moving means to release said latch members when said car is out of cooperative relation to said doorway.

7. In combination with a shaft, a car therein, and a door for closing a doorway in said shaft through which access may be had to said car when positioned opposite to said doorway, of an actuating element, means for locking said door closed, a member projectable into said shaft on actuation of said element and contacting with said car only when said car is positioned opposite to said doorway and limiting the projection of said member, further actuation of said element then acting to release said lock, said member being movable out of said limiting position by movement of said car after such contact to render said actuating element ineffective to release said lock while said car is in motion.

8. In combination with a shaft, a car therein, and a door for closing a doorway in said shaft through which access may be had to said car when positioned opposite said doorway, of a rock shaft carried by said door, means for locking the door closed, means actuatable by rocking said shaft for releasing said locking means only when said car is in cooperative relation to said doorway, and means associable with said locking means by which it may be released by the rocking of said shaft when the car is out of cooperative relation to said doorway.

9. In combination with a shaft, a car therein, and a door for closing a doorway in said shaft through which access may be had to said car when positioned opposite said doorway, of a bodily movable bar, means engageable between the ends of said

bar for moving the same, spring means adjacent opposite ends of said bar for holding the same against said moving means, one of said spring means being of less strength than the other, a door latch member operatively connected to said bar adjacent the stronger spring means and movable to door-released position on the bodily movement of the corresponding end of said bar, and means carried by the car acting to hold the other end of the bar when the elevator is in cooperative relation to said doorway, whereby actuation of said moving means effects release of said latch member, actuation of said moving means at other times acting to move the other end of said bar against the action of the weaker spring means without effecting the release of said latch member.

10. A lock comprising a bar fulcrumed at spaced points, means engageable with said bar for moving it about either of said fulcra, yielding means for said bar normally constraining it to move about one of said fulcra on the actuation of said movable means but permitting it to move about the other fulcrum when prevented from moving about said one fulcrum, a latch member actuatable only on the movement of said bar about said other fulcrum, and means associable with said lock for preventing the movement of said bar about said one fulcrum.

11. In combination with a shaft, a car therein, and a door for closing a doorway in said shaft through which access may be had to said car when positioned opposite said doorway, of a bar fulcrumed at spaced points, means engageable with said bar for moving it about either of said fulcra, yielding means for said bar normally constraining it to move about one of said fulcra on the actuation of said movable means but permitting it to move about the other fulcrum when prevented from moving about said one fulcrum, a latch member actuatable only on the movement of said bar about said other fulcrum, means for preventing movement of said bar about said one fulcrum when said car is in cooperative relation to said doorway, and other means associable with said lock for preventing the movement of said bar about said one fulcrum.

12. A device of the class described comprising a casing attachable to a door, a shaft journaled in said casing and accessible from without said door, a cam on said shaft within said casing, a bar movably supported in said casing, a comparatively weak spring engaging one end of said bar, a comparatively strong spring engaging the other end of said bar, both springs urging an intermediate portion of said bar against said cam, a member projectable without said casing carried by said one end of said bar and en-

gagable to prevent bodily movement thereof by the turning of said shaft, and a latch bolt projectable from said casing and operatively related to said other end of said bar.

13. A device of the class described comprising a casing attachable to a door, a shaft journaled in said casing and accessible from without said door, a cam on said shaft within said casing, a bar movably supported in said casing, a comparatively weak spring engaging one end of said bar, a comparatively strong spring engaging the other end of said bar, both springs urging an intermediate portion of said bar against said cam, a member projectable without said casing carried by said one end of said bar and engageable to prevent bodily movement thereof by the turning of said shaft, and a latch bolt projectable from said casing and operatively related to said other end of said bar, said casing having a keyhole through which a key may be inserted from outside the door in position to prevent bodily movement of said end of said bar.

14. In combination with a shaft, a car in said shaft, and a door for closing a doorway in said shaft through which access may be had to said car when positioned opposite said doorway, of a lock for said door comprising a casing, a bar movable in said casing, means engaging said bar intermediate its ends for moving said bar, a comparatively weak spring for engaging one end of said bar, a comparatively strong spring engaging the other end of said bar, both springs urging said bar against said moving means, a member yieldingly carried by said one end of said bar projecting from said casing into proximity to a part of said car when said car is in cooperative relation to said doorway to prevent bodily movement of said one end of said bar when said car is stationary in such position and movable out of operative relation to said bar by movement of said car, and a door lock member actuated by a bodily movement of the other end of said lever, whereby said lock member is normally actuatable by actuation of said bar-moving means only when said car is stationary in said position.

15. In combination with a shaft, a car in said shaft and a door for closing a doorway in said shaft through which access may be had to said car when positioned opposite said doorway, of a lock for said door comprising a casing, a bar movable in said casing, means engaging said bar intermediate its ends for moving said bar, a comparatively weak spring engaging one end of said bar, a comparatively strong spring engaging the other end of said bar, both springs urging said bar against said moving means, a member yieldingly carried by said one end of said bar projecting from said casing into proximity to a part of said car when said

car is in cooperative relation to said doorway to prevent bodily movement of said one end of said bar when said car is stationary in such position and movable out of operative position by movement of said car, and a door lock member actuated by a bodily movement of the other end of said lever, whereby said lock member is normally actuatable by actuation of said bar-moving means only when said car is stationary in said position, said casing having a key slot therein through which a key may be inserted in position to prevent bodily movement of said one end of said bar, whereby when said key is inserted said lock member is actuatable to unlock said door irrespective of the position or motion of said car.

16. A device of the class described comprising a casing, a rock shaft journaled transversely of said casing, a cam on said rock shaft within said casing, a pin projecting from one side of said casing, a bar loosely slidable on said pin, a comparatively weak spring engaging one end of said bar, a comparatively strong spring engaging the other end of said bar, both springs urging said bar along said pin with its intermediate portion into contact with said cam, a member carried by said one end of said bar and projecting from said casing where it may be engaged to prevent bodily movement of said one end on the turning of said rock shaft whereby the other end of said bar is moved thereby, a latch bolt slidably carried by said casing, a lever having one end engageable with said bolt for projecting and retracting the same, and means carried by the other end of said bar engaging the opposite end of said lever, whereby said bolt is projected by the movement of said bar against the action of said springs when said member is held, and whereby said member is projected without projecting said bolt when said member is not held.

17. A device of the class described comprising a casing, a rock shaft journaled transversely of said casing, a cam on said rock shaft within said casing, a pin projecting from one side of said casing, a bar loosely slidable on said pin, a comparatively weak spring engaging one end of said bar, a comparatively strong spring engaging the other end of said bar, both springs urging said bar along said pin with its intermediate portion into contact with said cam, a member carried by said one end of said bar and projecting from said casing where it may be engaged to prevent bodily movement of said one end on the turning of said rock shaft whereby the other end of said bar is moved thereby, a latch bolt slidably carried by said casing, a lever having one end engageable with said bolt for projecting and retracting the same, and means carried by the other end of said bar engaging the oppo-

site end of said lever, whereby said bolt is projected by the movement of said bar against the action of said springs when said member is held, and whereby said member is 5 projected without projecting said bolt when said member is not held, said casing having key slots therein through which a key may be inserted in the path of movement of said one end of said bar to prevent movement 10 thereof, whereby when said key is in position actuation of said cam actuates said bolt.

18. In combination with a shaft, a car in said shaft, a door for closing a doorway 15 in said shaft through which access may be had to said car when positioned opposite

thereto, a lock for said door, a member, and an element movable to project said member into the path of movement of said car when said car is out of position opposite 20 said doorway and to unlock said lock when said member is prevented from projecting by contact with said car when in stationary position opposite said doorway, said member being moved to a non-projected position by 25 movement of said car while contacted therewith, thereby being inoperative to cause the unlocking of said lock by movement of said element.

In testimony whereof I have affixed my 30 signature,

MARTIN B. McLAUTHLIN.
